UNITED STATES PATENT OFFICE.

GUSTAVE F. KRIESEL, OF MINNEAPOLIS, MINNESOTA, ASSIGNOR, BY MESNE ASSIGNMENTS, TO ESTHER V. SAFSTROM, OF MINNEAPOLIS, MINNESOTA.

BORING AND MILLING MACHINE.

1,415,878.

Specification of Letters Patent. Patented May 16, 1922.

Application filed April 24, 1918, Serial No. 230,412. Renewed September 10, 1921. Serial No. 499,863.

To all whom it may concern:

Be it known that I, GUSTAVE F. KRIESEL, a citizen of the United States, resident of Minneapolis, county of Hennepin, State of Minnesota, have invented certain new and useful Improvements in Boring and Milling Machines, of which the following is a specification.

The object of my invention is to provide an improvement in the machine shown and described in application for Letters Patent of the United States filed by me May 10, 1917, Serial No. 167,819.

The invention consists generally in various constructions and combinations, all as herein-after described and particularly pointed out in the claims.

In the accompanying drawings forming part of this specification,

20 Figure 1 is a plan view of a boring and milling machine embodying my invention,

Figure 2 is a vertical sectional view of the same,

Figure 3 is an end view,

25 Figure 4 is a detail sectional view, showing the feed gearing,

Figure 5 is a transverse sectional view of the feed mechanism,

Figure 6 is a sectional view, showing a 30 means for locking the shaft for a milling tool,

Figure 7 is a sectional view on the line 7—7 of Figure 4,

Figure 8 is a detail sectional view of the 35 feed mechanism,

Figure 9 is a detail sectional view of the means for changing the direction of movement of the feed shaft,

40 Figure 10 is a detail view showing one of the bars by means of which the work is clamped to the supporting plate,

Figure 11 is a sectional view on the line 11—11 of Figure 10,

45 Figure 12 is a sectional view on the line 12—12 of Figure 10.

In the drawing, 2 represents the base of the machine, having a horizontally projecting bracket 3 at the rear thereof. 4 is a shaft having a key-way 5 therein and 6 is a sleeve 50 having a key fitting said key-way and provided at one end with a gear 7. A bearing for said sleeve is provided in the bracket 3. A sleeve 8 is mounted in bearings in the upper part of the base and through this sleeve

the shaft 5 is thrust. One end of the shaft 55 has a tool holder 9 seated against a shoulder 10 in the end of the sleeve and at the opposite end of the sleeve the shaft is threaded and has a lock nut 11 for bearing on the end of the sleeve and holding the parts against 60 relative endwise displacement.

The shaft 4 is hollow, as shown, to adapt it to receive a rod that is used for centering the work with respect to the shaft and for adjusting the tools in the tool-carrying head. 65 This device, however, forms the subject matter of a separate application and I make no claim to the same herein.

The end of the base 2 is provided with an upright plate 12 having an opening 13 there- 70 in through which the sleeve 9 projects for the purpose of presenting the tool in position to work on the interior surface of a cylinder or other piece of work, which may be secured to the plate 12 over the opening 75 13, as described in my former application. 14 is a step pulley mounted on a drive shaft 15 that is geared at 16 to a shaft at 17 mounted in bearings in the base and the bracket 3 and having a pinion 18 meshing 80 with the gear 7 for revolving the shaft 5 within the sleeve 8. A shaft 19 is mounted in bearings 20 on said base and has a gear 21 thereon meshing with a gear 22 secured to the sheave 6 of the gear 7 and driven 85 thereby and provided with a loosely mounted worm 23 which meshes with a worm wheel 24 that is loosely mounted on a shaft 25 having a pinion 26 engaging the teeth of a rack 27 on the sleeve 8. The worm wheel 90 24 has a seat 26' formed therein for a friction clutch member 27 that is mounted to slide on the shaft 25 and normally held out of engagement with said seat by a spring 28. A hand wheel 29 engages the threads of 95 the shaft 25 for seating the clutch member 27 and temporarily locking the worm wheel on its shaft. The worm 23 has a clutch member 30 by means of which it is locked on the shaft 19 and a clutch shifter rod 31 has 100 a fork engaging the clutch and is free to slide in guides on the machine frame and the sleeve 8 has a block 32 that is movable back and forth on the rod 31 and a collar 33 is adjustable on said rod in the path of 105 said block to be actuated thereby for throwing out the clutch 30 at a predetermined point in the movement of the sleeve and

shaft. This clutch may be operated by hand whenever it is desired to disconnect the feed worm from its wheel.

For reversing the direction of movement 5 of the sleeve and shaft I provide a rod 34 having an operating handle 35 mounted to rock in bearings 36 and having a clutch connection at 37 with the gear 21. A pinion 38 is mounted on a shaft 39 and normally 10 meshes with the gear 22 on the shaft 4 and said gear 22 also meshes with a gear 21. A gear 40 is mounted on the shaft 39 and when it is desired to reverse the direction of movement of the worm the gear 21 is moved from 15 its position of engagement with the gear 22 into mesh with the gear 40, and thereupon the direction of revolution of the shaft 19 will be reversed. The shaft 34 is provided with a slot 41 and notches 42 leading thereto 20 and a pin 43 is mounted in the bearing 36 to enter these notches and lock the shaft 34 in its different adjustments. In the position shown in Figure 9, it is in engagement with the gear 22. When the shaft 34 is moved 25 lengthwise to enter the pin 43 in the notch at the other end of the slot, the gear 21 will then engage the gear 40 and in the intermediate notch the gear 21 will be in a neutral position between the pinion 36 and the 30 gear 40. At such time, if the clutch 30 is withdrawn, the worm 23 will be loose on the shaft and may turn freely thereon and the operator may regulate the feed by hand by means of a crank placed on the squared 35 end 44 of the shaft 25. In this way I am able to feed and retract the sleeve and the shaft supporting the tool holder and I may do this automatically or manually, as desired.

40 The upper part of the base has bearings 45 for a shaft indicated by dotted lines in Figure 2 for supporting a milling tool, said shaft projecting through an opening 46 provided in the upper part of the plate 12. 45 This shaft may be locked by suitable means, preferably a stud 47 having a recess 48 to receive the curved surface of the shaft and having a threaded end on which a lever 49 is mounted for moving the stud lengthwise 50 and clamping the walls of its recess against the surface of the shaft. A similar locking means may be provided for the sleeve 8, as indicated in Figure 2.

55 The plate 12 has work holders mounted thereon, consisting of bars 50, radially movable in guides 51 in said plate. These jaws are dovetailed to fit the correspondingly shaped walls of the guides 51 and are adapted to project into the opening 13 in the plate 60 12 and when the machine is used for cylinder boring or finishing, an annular flange 52 on the cylinder 53 will be gripped between these jaws, and plates 54 mounted on bolts 55 and having slots 56 for adjustment on said bolts. The bolts pass through holes in

the plate 12 and are tapped into plates 56' which have slots 57 therein to receive bolts 58 on which said plates are adjustable when the bolt nut is loosened and the head of the bolt 58 has a beveled face 59 to bear on the edge of the jaw 50 for locking it in its different radial adjustments. Suitable graduations are provided on the jaws to enable the workman to determine the proper degree of adjustment of the different jaws. 75

A bracket 60 is vertically adjustable in front of the table by means of an upright screw 61 and a shaft 62 geared thereto and on this bracket a work table 63 is mounted for adjustment transversely of the feed 80 shaft, or lengthwise thereof, as may be desired by means of the usual adjusting screws 64.

I claim as my invention:

1. The combination, with a frame having 85 an orifice and a surface around said orifice against which the piece of work is clamped, of a reciprocating member mounted in said frame for forward and backward movement with respect to said orifice, a tool-supporting 90 shaft fitting within said member to move forward and backward therewith and revolve therein, a drive shaft, a transmission shaft geared to said drive shaft and said tool-supporting shaft, and a second transmission shaft having a driving connection with said tool-supporting shaft and with said reciprocating member.

2. The combination, with a frame having an orifice and a surface around said orifice 100 against which the piece of work is clamped, of a reciprocating member mounted in said frame for forward and backward movement with respect to said orifice, a tool-supporting shaft fitting within said member to move forward and backward therewith and revolve therein, a drive shaft, and a transmission shaft geared to said drive shaft and having a forward and reverse driving connection with said tool-supporting shaft. 110

3. The combination, with a frame having an orifice and a surface around said orifice against which the piece of work is clamped, of a reciprocating member mounted in said frame for forward and backward movement 115 with respect to said orifice, a tool-supporting shaft fitting within said member to move forward and backward therewith and revolve therein, a drive shaft, a transmission shaft geared to said drive shaft and tool-supporting shaft and having forward and reverse driving connections with said reciprocating member.

4. The combination, with a frame, of a plate secured thereto and having an opening 125 therein, a sleeve mounted in said frame to project into said opening, a shaft within said sleeve having a tool carrier, means for clamping the work, such as a cylinder casting, against said plate and encircling the 130

opening therein, means for feeding said sleeve and shaft through said opening and revolving said shaft, and means for automatically checking said feeding movement 5 at a predetermined point in the movement of said sleeve.

5. The combination, with a frame having a face plate provided with an opening therein, of a sleeve mounted in bearings in 10 said frame to project through said opening, a shaft carried by said sleeve and having means for supporting a boring tool, said face plate having means for securing a piece of work to be bored against its face and encircling said opening, mechanism for feeding said sleeve and shaft and revolving said shaft within said sleeve and for reversing the direction of movement of said sleeve and shaft.

20. 6. The combination, with a frame having a face plate thereon with an opening therein and radial grooves provided in said plate, around said opening, jaws mounted to slide in said grooves and having slots therein, 25 bolts passing through said slots and through openings in the bottoms of said grooves and plates adjustable on said bolts and between which and said jaws the work is clamped against said face plate and encircling the 30 opening therein, and a boring tool supporting shaft operating through said opening.

7. The combination, with a face plate having an opening therein and radial grooves around said opening provided with 35 slots in the bottoms thereof, of jaw plates having slots therein and slidable in said grooves, bolts fitting within the slots in said jaw plates and having clamping plates on one end thereof between which and said 40 jaw plates the work is gripped, and adjustable plates mounted on the other end of said bolts for engagement with the opposite side of said face plate and a boring tool supporting means operating through the opening in 45 said face plate.

8. The combination, with a face plate having an opening therein and radial grooves around said opening provided with slots in the bottom thereof, jaws slidable in said 50 grooves and having slots therein, bolts passing through the slots in said jaws, and clamping plates carried by said bolts between which and said jaws the work is gripped, bolts having heads for locking said 55 clamping jaws in their adjusted positions and plates mounted on said first named bolts and having slots therein to receive said jaw clamping bolts for adjustment thereon with the movement of said first named bolts, 60 and a boring tool supporting means operating through the opening in said plate.

9. The combination, with a frame having a face plate provided with an opening therein, of a member mounted in bearings 65 in said frame and means for feeding it

toward and from said opening, a shaft carried by said member and having means for supporting a tool, means for revolving said shaft independently of its forward feeding movement with said sleeve and means for 70 clamping the work on said plate around said opening, the tool carried by said shaft projecting into and operating through the opening in said plate.

10. The combination, with a frame having a face plate thereon provided with an opening and radial grooves in said plate around 75 said opening, jaws mounted to slide in said grooves, bolts mounted in said jaws and fitting openings in the bottoms of said grooves, plates adjustable on said bolts and between 80 which and said jaws the work is clamped against said face plate, and a tool supporting shaft operating through the opening in said face plate.

11. The combination, with a face plate having an opening therein and radial grooves around said opening, and slots in the bottom of said grooves, of jaw plates slidable in said 90 grooves, bolts mounted for adjustment in said jaw plates and having clamping plates between which and said jaw plates the work is gripped, and means mounted on said bolts for engagement with the opposite side of 95 said face plate, and a tool supporting means operating through the opening in said face plate.

12. The combination, with a frame having an orifice and a surface around said orifice against which the piece of work is clamped, 100 of a reciprocating member mounted in said frame for forward and backward movement with respect to said orifice, a tool-supporting shaft fitting within said member to move forward and backward therewith and revolve 105 therein, a drive shaft, a transmission shaft geared to said drive shaft and said tool-supporting shaft and having forward and reverse driving connections with said tool-supporting shaft and said reciprocating 110 member.

13. The combination, with a frame having an orifice and a surface around said orifice against which the piece of work is clamped, 115 of a reciprocating member mounted in said frame for forward and backward movement with respect to said orifice, a tool-supporting shaft fitting within said member to move forward and backward therewith and revolve 120 therein, a drive shaft, a transmission shaft geared to said drive shaft and said tool-supporting shaft and having forward and reverse driving connections with said tool-supporting shaft and said reciprocating member, the connections with said reciprocating member permitting it to be operated 125 by power or manually.

14. The combination, with a frame having an orifice and a surface around said orifice against which the piece of work is clamped, 130

of a reciprocating member mounted in said frame for forward and backward movement with respect to said orifice, a tool-supporting shaft fitting within said member to move forward and backward therewith and revolve therein, a drive shaft, a transmission shaft geared to said drive shaft and having a forward and reverse driving connection with said tool-supporting shaft, a second transmission shaft, a worm loosely mounted thereon, a clutch for locking said worm, a worm wheel engaging said worm and having a driving connection with said reciprocating member, and means for locking or releasing said worm wheel.

15. The combination, with a frame having an orifice and a surface around the orifice against which the piece of work is clamped, of a reciprocating member mounted in said frame for forward and backward movement with respect to said orifice, a tool-supporting shaft having bearings in said member to move forward and backward therewith and revolve therein, a drive shaft, a transmission shaft geared to said drive shaft and to said tool supporting shaft, a second transmission shaft having a driving connecting with said tool-supporting shaft, a transverse shaft having a rack and pinion driving connection with said reciprocating member, a worm mounted on said second transmission shaft, a worm wheel loosely mounted on said transverse shaft and engaging said worm and means for locking said worm wheel to re-

35 move said transverse shaft or releasing said worm wheel to allow it to run idle and said transverse shaft to be operated manually.

16. The combination, with a frame having an orifice therein and a surface around said orifice against which a piece of work to be bored is clamped, of a sleeve mounted to reciprocate in said frame, forward and backward with respect to said orifice, a shaft mounted in said sleeve and having means for supporting a tool to engage the work through said orifice, means for revolving said shaft in said sleeve, and means for locking said sleeve against forward and backward movement.

17. The combination, with a frame having 50 an orifice therein and a surface around said orifice against which a piece of work to be bored is clamped, of a sleeve mounted to reciprocate in said frame, forward and backward with respect to said orifice, a shaft 55 mounted in said sleeve and having means for supporting a tool to engage the work through said orifice, means for revolving said shaft in said sleeve, and means for locking said sleeve against forward and backward movement, said means including a stud having a recess therein to fit the surface of said sleeve and means for moving said stud lengthwise 60 to engage the wall of said recess with the surface of said sleeve.

In witness whereof, I have hereunto set my hand this 27th day of March, 1918.

GUSTAVE F. KRIESEL.
